UNITED STATES PATENT OFFICE.

HASKETT D. EASTMAN, OF MINNEAPOLIS, MINNESOTA.

FIRE-ESCAPE.

SPECIFICATION forming part of Letters Patent No. 275,895, dated April 17, 1883.

Application filed October 11, 1882. (No model.)

To all whom it may concern:

Be it known that I, HASKETT D. EASTMAN, of Minneapolis, in the county of Hennepin and State of Minnesota, have invented a new and Improved Fire-Escape, of which the following is a full, clear, and exact description.

The object of my invention is to provide a means for the ready escape of persons from burning buildings, and also to facilitate the work of firemen upon such buildings.

The invention consists in the peculiar construction and arrangement of the parts, as hereinafter more fully set forth, and pointed out in the claims.

Reference is to be had to the accompanying drawings, forming a part of this specification, in which similar letters of reference indicate corresponding parts in both the figures.

Figure 1 is a front elevation of my improved fire-escape. Fig. 2 is a side view of the same.

The supports of the fire-escape consist of a frame, A, constructed of tubes *a*, of suitable size, connected together in lengths by couplings *b* at the several stories of the building. The frame is preferably constructed, as shown, of two parallel lines of tubes, connected at the top and bottom by cross-tubes *c*, and at the bottom both lines of vertical tubing are to be connected with the street water-main by a pipe, as shown at *d*; or a coupling may be provided at that place for connection of the hose from the engine. The couplings *b* are formed as T's, that are adapted for connection of the hose-pipe, as shown at *e* in Fig. 1. Beneath each of these connections *b* the vertical pipes *a* are fitted with a platform or balcony, *f*, these balconies being clamped firmly to the pipes and made of a suitable size for the use of firemen in manipulating the hose. At one or both sides the balconies *f* are connected by an iron ladder, *g*, which extends from the ground to the upper balcony for the use of the firemen in ascending and descending, and which may also be used for the escape of persons from the building. At its upper end the frame A is fitted with boxes *i*, that support a cross-shaft, *k*, carrying two chain-wheels, *l l'*, and at its lower part, or near the ground, the frame is fitted with a similar cross-shaft, *k'*, carrying chain-wheels *l' l''*. Around the chain-wheels *l l'* are endless chains *m*, and to these chains, at suitable intervals, buckets or cars *n* are attached, these cars being of a size for holding

two or more persons. The lower shaft, *k'*, extends at one side, and is provided with a gear-wheel, *p*, which is engaged by the pinion *q* on a crank-shaft, *r*. The shaft *r* is also provided with a heavy fly-wheel, *s*, to which a hand-brake, *t*, is fitted for use in regulating the descent of the loaded cars. The frame A is to be attached to the outside of the building by supports of any suitable character, and may remain as a permanent construction, ready for use at any time.

With a fire-escape apparatus of this construction persons and goods can be readily placed in the cars *n* from the windows of the building and lowered safely to the ground, the descent being regulated by means of the handle of the crank-shaft or by the brake. The cars being of suitable size, timid persons, women, or children placed in them can be safely lowered without danger of their falling out. The ladder furnishes an independent means for the use of the firemen in ascending at the front of the building, and, water being supplied to the stand-pipes, the hose can be attached wherever desired and readily manipulated from the balconies to throw the water to the desired place.

Instead of being attached to a building, the apparatus may be made as a portable machine for use with low buildings. In that case it will be mounted on wheels, and made in two portions hinged together, the upper portion to be arranged for being raised and lowered by a windlass and ropes.

Having thus described my invention, I claim as new and desire to secure by Letters Patent—

1. In fire-escapes, the frame A, composed of tubes connected together by T-couplings *b*, and provided with shafts, chain-wheels, and endless chains carrying buckets or cars, substantially as described, so as to serve the double purpose of a water stand-pipe and a fire-escape, as set forth.

2. In fire-escapes, the combination, with an endless-chain elevator, of a water stand-pipe provided at suitable intervals with couplings for connection of hose, and forming one or more sides of the supporting-frame of the fire-escape, substantially as described.

HASKETT DERBY EASTMAN.
